UNITED STATES PATENT OFFICE.

CLARA M. HINKLEY, OF PITTSBURG, PENNSYLVANIA.

DESIGN FOR A HAIR-PIN.

SPECIFICATION forming part of Design No. 26,880, dated April 13, 1897.

Application filed January 14, 1897. Serial No. 619,252. Term of patent 14 years.

To all whom it may concern:

Be it known that I, CLARA M. HINKLEY, a citizen of the United States, residing at Pittsburgh, in the county of Allegheny, State of Pennsylvania, have invented and produced a new and original Design for a Hair-Pin; and I do hereby declare the following to be a full, clear, and exact description of the invention, such as will enable others skilled in the art to which it appertains to make and use the same.

My invention relates to a new and original design for a hair-pin.

By the use of the style of hair-pins now so universally used it is well known that they occasion much trouble and annoyance owing to the fact that they so easily slip out from the wearer's hair. The object of my invention is to obviate this trouble by the production of a hair-pin attractive in appearance and one that may be cheaply and artistically manufactured.

The leading feature of my design consists of a two-pronged hair-pin having conical-shaped enlargements on each of the prongs, all of which will be more fully hereinafter described.

My invention is illustrated in the accompanying drawings, in which—

Figure 1 is a front view in elevation; Fig. 30 2, a similar view showing more enlargements than those shown in Fig. 1, and Fig. 3 a cross-section on line *xx* of Fig. 1.

Referring to the drawings, A represents a two-pronged pin made of any suitable material and of any desirable size.

Bare conical enlargements preferably made integral with the prongs of the pin and in such a manner that at the point *a* they are flush with the prongs and have a gradual 40 swell, terminating in rounded shoulders *b*. These enlargements may be made of the same material as the pin or may be made of other suitable material. The length and swell of the enlargements, as well as the number of 45 them, may vary without departing from the spirit of my invention so long as the general design herein shown is not departed from.

Having thus described my invention, what I claim is—

The design for a hair-pin, substantially as herein shown and described.

In testimony whereof I affix my signature in presence of two witnesses.

CLARA M. HINKLEY.
